UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed November 10, 1928. Serial No. 318,353.

This invention relates to keyboards for typewriting and other machines, and is mainly for the use and benefit of the blind.

This invention provides simple, practical, sensorial identification signs for the keyboard, whereby the sightless, with their highly sensitive finger-tips, can quickly learn to operate a typewriting machine through the touch system. A wide field of useful occupation or enjoyable pursuit is therefore opened to the blind, who can use the machine with facility. Furthermore the means employed are inexpensive, easily applied, instantly understood and of lasting construction.

In the design shown, the key-caps, which are preferably of stamped metal, are formed to fit over the standard keys of a machine and are locked thereon. These caps have raised, partly spherical projections or "points" on their top surfaces, said projections being deployed or grouped to be identical with the signs of the Braille alphabet and numeral system, now in use for the blind. Said groups have the same dimensions as those of said Braille system, and when applied to the keys bear the same definite relation to one another as do the signs in books that are embossed especially for the blind.

Due to the small dimensions of the embossed groups, their meaning is instantly comprehended when touched, because a blind person does not have to feel around a large area for the identification signs. Where the

latter are used with keys having two symbols, the keys will have two corresponding groups of embossings, which will be located in upper and lower case positions. These keys or their caps can bear additional intermediately embossed projections on their surfaces, whereby a blind operator can sense that two distinct groups are carried by said caps. These intermediate embossings are valuable in identifying the numeral-keys, because the Braille signs for numerals are the same as for the first ten letters of the alphabet. These intermediate embossings, however, can be omitted.

As it is necessary to maintain a fixed relation between the separate groups of signs, each cap is locked on the key through a

forked tab, said tab being bent under the key to tightly engage the sides of the key-stem. Other tabs are also provided on each cap, which are bent under to hold the cap more firmly on its key. When forming the tabs they are preferably located 120 degrees apart, with the forked tab at the rear. In such locations said tabs, when bent under the key, will have a direct hold on the latter, and will not overlap or interfere with other tabs used for securing the rims of the standard keys.

The aforementioned embossed caps have been described as applied over the standard keys found in a keyboard. When so desired, however, the embossed caps can be directly applied at the factory to the platforms of the key-stems. This will save some weight and expense. In order to be readily distinguishable by one not versed in the Braille signs, the embossed caps can be stamped with the corresponding letter or symbol, as shown in the drawings. A purchaser or workman can, therefore, correctly position the caps on the corresponding keys.

Other features and advantages will hereinafter appear.

In the accompanying drawings,

Figure 1 is a top view of a keyboard which embodies this invention.

Figure 2 is an enlarged view of a key-cap as embossed for the letter "R", and shows the relative spacing of the two sets of tabs.

Figure 3 is a vertical sectional view on the line 3-3 of Figure 2, and shows the embossed cap applied over the standard key.

Figure 4 is a side elevation of a key, showing the long tab partly encompassing the key-stem.

Figure 5 is a vertical sectional view of a key-stem platform, showing the key-cap directly applied thereto.

Figure 6 is a top plan of a key-cap which has two groups of identification signs, and also intermediate signs to indicate the presence of said two groups.

Figure 7 is a front elevation of a key-cap, and shows quotation marks and a nu-

meral stamped on the front of said key-cap for identification of the signs thereon.

Figure 8 is a front elevation of a key-cap before the tabs are bent.

Figure 9 is an enlarged diagrammatic view of a standard Braille cell or unit.

Referring to the drawings, key-caps 10 have annular flanges 11 and tabs 12 and 13. The latter are longer than said tabs 12 and 10 and also are forked, as at 14. The top surfaces of the key-caps 10 are embossed with raised, partly spherical projections 15, which conform with the signs used in the Braille system. Intermediate projections 16 can be used on key-caps 17, whereon two different groups of signs are used, as shown at 18 and 19.

The key-caps 10 are ordinarily applied over the keys 20 of a keyboard 21, and in the same standard relation to each other. The keys 20 have platforms 22, printed disks 23, transparent material 24, rims 25 and tabs 26 thereon, the platform forming part of key-stems 27. After the caps have been applied over the keys the tabs 12 and 13 are bent in and under said platforms, and will interlie the tabs 26. Also the key-caps are so applied to the keys that the tabs 13 will straddle and tightly engage the rear 30 of the key-stems 27 and will hold said caps against rotating.

When desirable, the key-caps 10 can be attached directly to the platforms 22, as in Figure 5, and thus save the cost and expense of making and applying the parts 23, 24, 25 and 26. In Figure 1 are shown a spacing bar 28, shift-keys 29, a back-spacing key 30 and a tabulator-key 31. The parts numbered 28, 29, 30 and 31 have no 40 key-caps, because, through their widely-separated positions and lack of signs, a blind operator will soon learn their import.

Variations may be resorted to within the scope of the invention, and portions of the improvements may be used without others.

Having thus described my invention, I claim:

1. In typing and other machines, a group of keys for the use of the blind and which form a keyboard, said keys including platforms and stems, caps having slightly convex top surfaces, there being one cap for each symbolic key, integral annular flanges on said caps, integral extensions on said flanges, forked ends on one of said extensions on each cap, and raised spherical segments or "points" which are integral with said surfaces, said segments positioned, deployed or grouped in different arrangement on each cap to form signs, said caps superposed on and around said platforms, said extensions being bent under the latter, said forked ends engaging the sides of said stems, to hold said caps non-rotational on said platforms, and said segments or "points" to be respectively identical in arrangement with, and confined within, the same areas as the corresponding signs of the Braille system.

2. In typing and other machines, a group of keys for the use of the blind and which form a keyboard, said keys including platforms and stems, caps having slightly convex top surfaces, there being one cap for each symbolic key, integral annular flanges on said caps, integral extensions on said flanges, forked ends on one of said extensions on each cap, and raised spherical segments or "points" which are integral with said surfaces, said segments positioned, deployed or grouped in different arrangement on each cap to form signs, said caps superposed on and around said platforms, said extensions being bent under the latter, said forked ends engaging the sides of said stems to hold said caps non-rotational on said platforms, and said segments or "points" to be respectively identical in arrangement with, and confined within, the same areas as the corresponding signs of the Braille system.

2. In typing and other machines, a group of keys for the use of the blind and which form a keyboard, said keys including platforms and stems, caps having slightly convex top surfaces, there being one cap for each symbolic key, integral annular flanges on said caps, integral extensions on said flanges, forked ends on one of said extensions on each cap, and raised spherical segments or "points" which are integral with said surfaces, said segments positioned, deployed or grouped in different arrangement on each cap to form signs, said caps superposed on and around said platforms, said extensions being bent under the latter, said forked ends engaging the sides of said stems to hold said caps non-rotational on said platforms, and said segments or "points" to be respectively identical in arrangement with, and confined within, the same areas as the corresponding signs of the Braille system, and some caps each having two signs and also integral raised projections intermediate said two signs, whereby such dual grouping of the Braille signs can be sensed by the blind, and each sign thereof can convey its respective meaning without confusion.

3. In typing and other machines, a group of keys for the use of the blind and which form a keyboard, said keys including platforms and stems, caps having slightly convex top surfaces, there being one cap for each symbolic key, integral annular flanges on said caps, integral extensions on said flanges, forked ends on one of said extensions on each cap, raised spherical segments or "points" which are integral with said surfaces, said segments positioned, deployed or grouped in different arrangement on each cap to form signs, said caps superposed on and around said platforms, said extensions being bent under the latter, said forked ends engaging the sides of said stems, to hold said caps non-rotational on said platforms, and said segments or "points" to be respectively identical in arrangement with, and confined within, the same areas as the corresponding signs of the Braille system, and symbols on each of said flanges, said symbols corresponding respectively with said segments or "points" with which they are associated, whereby the signs on the caps, which are understood by the blind, can be identified by those with sight who do not know said system.

4. In typing and other machines, a group of keys for the use of the blind and which form a keyboard, said keys including platforms and stems, caps having slightly convex top surfaces, there being one cap for each symbolic key, integral annular flanges on said caps, integral extensions on said flanges, forked ends on one of said extensions on each

- cap, and raised spherical segments or "points" which are integral with said surfaces, said segments positioned, deployed or grouped in different arrangement on each cap within, the same areas as the corresponding signs of the Braille system, and raised letters, numerals or marks on said flanges, which respectively correspond on each cap with the Braille sign thereon, so the blind 70 who understand the Braille system can also sense the conformation of the accompanying letters, numerals or marks.
- 5 to form signs, said caps superposed on and around said platforms, said extensions being bent under the latter, said forked ends engaging the sides of said stems, to hold said caps non-rotational on said platforms, and said 75 segments or "points" to be respectively identical in arrangement with, and confined within, the same areas as the corresponding signs of the Braille system, and some keys not having said segments or projections, such 80 last-mentioned keys being readily discernible for this reason, whereby they can be readily identified through location and touch, and can convey their pre-explained purposes to the minds of the blind.
- 10 20 5. In typing and other machines, a group of keys for the use of the blind and which form a keyboard, said keys including platforms and stems, caps having slightly convex top surfaces, there being one cap for each 85 symbolic key, integral annular flanges on said caps, integral extensions on said flanges, forked ends on one of said extensions on each cap, raised spherical segments or "points" which are integral with said surfaces, said 90 segments positioned, deployed or grouped in different arrangement on each cap to form signs, said caps superposed on and around said platforms, said extensions being bent under the latter, said forked ends 95 engaging the sides of said stems, to hold said caps non-rotational on said platforms, and said segments or "points" to be respectively identical in arrangement with, and confined within, the same areas as the corresponding signs of the Braille system, and a spacing bar without said segments or projections, which is easily discernible for this reason and through shape and location, whereby when touched it is identified by the blind, who can correctly operate the same when its use has been explained.
- 15 30 6. In typing and other machines, a group of keys for the use of the blind and which form a keyboard, said keys including platforms and stems, caps having slightly convex top surfaces, there being one cap for each symbolic key, integral annular flanges on said caps, integral extensions on said flanges, forked ends on one of said extensions on each cap, raised spherical segments or "points" which are integral with said surfaces, said segments positioned, deployed or grouped in different arrangement on each cap to form signs, said caps superposed on and around said platforms, said extensions being bent under the latter, said forked ends engaging the sides of said stems, to hold said caps non-rotational on said platforms, and said segments or "points" to be respectively identical in arrangement with, and confined 35 40 45 50 55 60 65 70 75 80 85 90 95
7. In typing and other machines, a group of keys forming a keyboard, lettered platforms and stems forming part of said keys, caps detachable from said keys, raised Braille "points" on the top surfaces of said caps, said "points" positioned, deployed or grouped in different arrangement on each cap, integral annular flanges on said caps, integral extensions on the caps, and forked ends on one of said extensions on each cap, said extensions being flexible to permit successive attachment to or removal of said caps, so a blind operator may first become familiar with the locations of said raised signs on said platforms, after which they may be removed to test the operator's memory for location, and if at fault the caps can again be attached, whereby the blind are aided in memorizing the respective locations of the keys, to more readily learn to operate the keyboard through the "touch system", or the seeing may learn to operate said keyboard through familiarization with said signs on said platforms and caps.
